UNITED STATES PATENT OFFICE.

OTTO A. GIFFEN, OF HANOVER, OHIO.

GAS-CUT-OFF VALVE.

No. 919,155.

Specification of Letters Patent. Patented April 20, 1909.

Application filed November 18, 1907. Serial No. 401,995.

To all whom it may concern:

Be it known that I, OTTO A. GIFFEN, a citizen of the United States, residing at Hanover, in the county of Licking, State of Ohio, have invented certain new and useful Improvements in Gas-Cut-Off Valves; and I do hereby declare the following to be a full, clear, and exact description of the invention, such as will enable others skilled in the art to 10 which it appertains to make and use the same.

The present invention has reference to cut-off valves for gas-supply systems, and it aims, generally, to provide an exceedingly simple, inexpensive, and effective device of that nature adapted to automatically shut off the entire supply of gas from the burners, should the pressure become so low as to fail to support combustion at the burners, and to 20 remain in its closed position after the pressure rises, until opened manually.

The invention further resides in the provision of a supplemental cut-off valve the interior of whose casing is in communication 25 with that of the main valve, this supplemental valve being closed automatically by the gas escaping from the inlet chamber of the main valve when the pressure of the gas suddenly rises after having fallen to an extent sufficient to permit the closure of the main valve.

The invention still further resides in the particular construction of the main valve casing and its plug, in which latter the upper 35 valve seat is formed; in the particular means provided for raising the main valve into its open position in such seat; and in the construction of the supplemental valve and its casing; and the manner of connecting the 40 same with the casing of the main valve.

The invention will be readily understood from a consideration of the following detailed description, and its preferred embodiment is illustrated in the accompanying drawings in 45 which like parts, or features, as the case may be, are designated by corresponding reference numerals in the several views.

Of the said drawings:—Figure 1 is a vertical section through the device. Fig. 2 is an enlarged section through the plug. Fig. 3 is an enlarged section through the casing of the supplemental valve, showing the latter in place therein. Fig. 4 is an enlarged section 50 through a modified form of plug and the valve used in connection therewith. Fig. 5

is a detail view of a modified form of the operating rod.

Referring more particularly to the drawings, 7 designates, generally, the main valve casing which forms a union with the two sections of the service pipe, not shown, the left-hand section supplying gas to the burners. The casing is provided with the usual S-shaped partition 9 which divides the interior of the casing into upper and lower compartments 10 and 11 and has an opening 12 formed through the central or horizontal portion thereof, such opening serving as the lower seat for the valve 13, which latter is, in the main, similar to a check-valve, and includes a central body portion and vertical 60 guide arms formed in opposite sides thereof.

The top of the casing is provided with a threaded opening adapted to receive the stem of a plug 14 having a vertical passage 15 formed therethrough, the under cut lower end 16 of the stem forming the upper valve seat, the upper arms of the valve extending into said passage when the valve is in its raised or open position. The stem is further 70 provided at its lower end with a depending annular shoulder 17, which is formed on the outer edge thereof, as shown in Fig. 2, and thus serves as a casing for the seat 16, preventing bodily sidewise movement of the 75 valve, when raised thereinto, and its consequent displacement therefrom when the casing is subjected to any vibrations. The upper portion of the passage 15 is likewise threaded, and is adapted to receive the lower 80 end of a pipe section 18 to which the casing 19 of the supplemental valve 20 is connected. This casing is likewise divided into upper 85 and lower compartments by a partition 21 provided with an opening 22 forming a seat 90 for the valve when the latter is in its raised or closed position.

The bottom of the main casing 7 is provided with a depending shoulder 23 having a threaded vertical passage formed therethrough and communicating at its upper end with the lower compartment 11. Through this passage extends a threaded rod 24 whose outer end has secured thereto a hand wheel 25 by means of which the rod is turned in one direction or the other, to effect an endwise movement thereof. This rod serves as a means for raising the main valve 13 into its open position, or, in other words, into its upper seat 16, wherein it is held by the pres- 105 110

sure of the gas until such pressure decreases to an extent sufficient to permit the valve to fall of its own weight into its lower seat 12. In the preferred construction of the rod, its length is such that its upper end may be moved into contact with the under face of the valve body, whereupon a further upward movement of the rod will carry the valve into its upper seat. In the modified construction shown in Fig. 5, the rod, at the limit of its upward movement, terminates short of the valve which latter rests upon the upper end of an expansible coil-spring 26 whose lower end is made fast to the upper 15 end of the rod, the spring thus exercising an upward pressure against the valve, as will be apparent. In both constructions the downward movement of the rod is limited and its complete removal prevented by the 20 provision of a shoulder 27 formed integrally upon the rod intermediate the ends thereof. A certain limitation of the upward movement of the rod is likewise effected by the provision of a packing nut 28 which is adjustable upon the threaded portion of the shoulder 23 and has an opening through which the rod extends. The position of this nut, against which the wheel 25 contacts when the rod has been advanced a certain 25 distance, therefore regulates the extent of such advance, as will be apparent, it being thus possible to prevent the valve from being moved too forcibly into its upper seat. The same effect is accomplished by the use 30 of the spring.

In the operation of this form of the device, the normal pressure of the gas beneath the main valve will hold the latter in its raised or open position, the gas being thus free to 40 pass through the opening 12 and through the lower compartment 11 to the supply pipe for the burners until the pressure decreases to an extent sufficient to permit the valve to fall of its own weight and fit in said opening, thus cutting off any further supply to the burner pipe. The pressure of the incoming gas is insufficient, however, to raise the valve 20 into its closed position, so that the gas is free to pass through the opening 22 45 into the upper compartment of the casing, from which it exhausts through the mouth of a turn-cock 29 carried by said casing. When the gas pressure again rises to normal, the main valve will be retained in its closed 50 position by the pressure thereupon, and the valve 20 will likewise be raised into closed position by the pressure therebeneath. The rod 24 is then moved upwardly by means of its hand wheel 25, so as to raise the main 55 valve into its upper seat, whereupon the gas is again free to flow into the burner pipe, the supplemental valve being returned to its normal position after the main valve has risen.

60 In the modified construction shown in Fig.

4, the supplemental casing 19 and the pipe section 18 are replaced by a cap or dome 30 whose threaded stem fits in the upper end of the passage 15 in the plug. The flat under face of this cap is provided with a threaded 70 opening adapted to receive the upper end of a cylindrical valve casing 31 within the bore of which is disposed the stem of a valve 32, the lower end of the valve stem resting upon an expansible coil-spring 33 likewise fitted in said bore, which latter is reduced at its lower end. The flat head of the valve 32 is thus held normally above the upper end of the casing, such movement being limited by a finger 34 having a lateral projection adapted 80 to extend across the valve head. The lower end of the last-mentioned casing carries a turn-cock 35 threaded thereto, although this element may be disposed opposite the casing with its stem fitted in an opening formed in the cap bottom. The operation of the modified construction is similar to that of the preferred form and therefore requires no further illustration. It is to be understood, however, that the cap 30 is itself 90 a supplemental casing provided with an interiorly-located valve, so that the term "supplemental casing" occurring in the claims may refer with equal propriety to both the preferred and the modified construction. 95

The end of the inlet pipe which is fitted in the main casing is preferably provided with a screen of wire gauze secured thereto in any desired manner for preventing the entry of any foreign matter with the gas into the 100 casing.

What is claimed is:—

1. In a gas cut-off, the combination, with a casing provided with a partition having a valve seat formed therein, of a plug fitted in the top of the casing and having a valve seat formed in its lower end, a valve movable between said seats and adapted to seat in one or the other, and a threaded rotatable rod extending through the bottom of the casing 105 and provided with a resilient member adapted to contact with the valve, to raise the valve from its lower seat into its upper seat. 110

2. In a gas cut-off, the combination, with a main casing provided with an inlet and an outlet compartment, of a supplemental casing communicating with the inlet compartment and with the atmosphere, a main vertically-movable pressure-operated valve for cutting off communication between the inlet 115 compartment and the supplemental casing when the gas pressure is normal, and between the inlet and outlet compartments when the pressure falls below normal, a pressure-operated valve located within the supplemental casing for cutting off communication between the inlet compartment and the atmosphere when the gas-pressure subsequently rises to normal, and a threaded rotatable rod extending through the bottom of 120 125 130

the main casing, for raising said main valve, in the last-mentioned instance, to re-open communication between said inlet and outlet compartments.

- 5 3. In a gas cut-off, the combination, with a main casing provided with an inlet and an outlet compartment, of a supplemental casing communicating with the inlet compartment and with the atmosphere, a main vertically-movable pressure-operated valve for cutting off communication between the inlet compartment and the supplemental casing when the gas pressure is normal, and between the inlet and outlet compartment 10 15 when the pressure falls below normal, a pressure-operated valve located within the supplemental casing for cutting off communication between the inlet compartment and the atmosphere when the gas-pressure 20 subsequently rises to normal, and an end- 25 wise movable rod extending through the bottom of the main casing and provided with a resilient member located within the interior of said casing and adapted to contact with said main valve for raising the same, in the last-mentioned instance, to re-open communication between said inlet and outlet compartments.
4. In a gas cut-off, the combination, with 30 a main casing provided with an inlet and an outlet compartment, of a supplemental casing communicating with the inlet compartment and with the atmosphere, a main vertically-movable pressure-operated valve for 35 cutting off communication between the inlet compartment and the supplemental casing when the gas pressure is normal, and between the inlet and outlet compartments when the pressure falls below normal, a 40 pressure-operated valve located within the supplemental casing for cutting off communication between the inlet compartment

and the atmosphere when the gas-pressure subsequently rises to normal, and a threaded rotatable rod extending through the bottom 45 of the main casing and provided with a resilient member located within the interior of said casing and adapted to contact with said main valve, for raising the same in the last-mentioned instance, to re-open communication 50 between said inlet and outlet compartments.

5. In a gas cut-off, the combination, with a casing provided with inlet and outlet compartments, of a supplemental casing communicating with the inlet compartment, a bored valve casing carried by the supplemental casing a valve having its stem fitted in said bore, and a spring fitted in said bore and bearing against the inner end of the 60 valve stem for normally holding the valve in open position.

6. In a gas cut-off, the combination, with a casing provided with inlet and outlet compartments, of a supplemental casing communicating with the inlet compartment, a bored valve casing carried by the supplemental casing, a valve including a head portion adapted to rest upon one end of the valve casing to close the bore and a stem 70 extending into the bore, a spring disposed within the bore and bearing against the inner end of the stem, to normally force the valve head away from said valve casing, and a member extending across the path of movement of the valve head, to limit such movement.

In testimony whereof, I affix my signature, in presence of two witnesses.

OTTO A. GIFFEN.
